(57) **CLAIM**

I claim the ornamental design for a cigar stand, as shown and described.

DESCRIPTION

FIG. 1 is a perspective view of our new design for a cigar stand;

FIG. 2 is a front view thereof;

FIG. 3 is a top plan view thereof;

FIG. 4 is a bottom view thereof;

FIG. 5 is a left side thereof, the right side being a mirror image thereof.

FIG. 6 is a top plan view of two component parts that join together at their respective slots for forming our new design for the cigar stand shown in FIGS. 1-5; and,

FIG. 7 is a perspective-view of the component parts shown in FIG. 6.
